Patented July 19, 1921.

UNITED STATES PATENT OFFICE.

MILBOURNE KEITH DUNHAM, OF NEW YORK, N. Y., ASSIGNOR OF ONE-THIRD TO
CHARLES BERG AND TWO-THIRDS TO WILLGOT KLINGBERG, BOTH OF NEW
YORK, N. Y.

HEATER.

1,384,746.

Specification of Letters Patent. Patented July 19, 1921.

Application filed January 22, 1918. Serial No. 213,128.

To all whom it may concern:

Be it known that I, MILBOURNE KEITH DUNHAM, a citizen of the United States, residing at New York, in the county and 5 State of New York, have made a certain new and useful Invention in Heaters, of which the following is a specification.

This invention relates to combustion engine heaters.

10 The object of the invention is to provide a heater, which is simple in structure, efficient in use and economical of manufacture.

The further object of the invention is to 15 provide a heater which does not increase fire hazard when used in connection with the automobile.

A further object of the invention is to provide heater, which is water jacketed.

20 A further object of the invention is to provide a heater which does not transmit the vibrations of the motor to the car body and which allows the heater to be of any desired finish without danger of cracking or other disfigurement thereof.

25 A further object of the invention is to provide a heater which may be readily controlled and which has in connection therewith, various features to make the same safe against explosion and against injury, due 30 to the water in the water jacket thereof, from freezing.

A further object of the invention will appear more fully hereinafter.

The invention consists substantially in 35 the construction, combination, location and relative arrangement of parts all as will be more fully hereinafter set forth, as shown in the accompanying drawing and finally pointed out in the appended claims.

40 Referring to the drawing,

Figure 1 is a sectional view in front elevation of a heater embodying my invention.

Fig. 2 is a sectional view taken on the line 2-2, Fig. 1 and looking in the direction of the arrows.

Fig. 3 is a sectional view taken on the line 3-3 Fig. 1 and looking in the direction of the arrows.

Fig. 4 is a sectional view taken on the line 4-4, Fig. 1 and looking in the direction of the arrows.

Fig. 5 is a top plan view of a portion of a modified structure of heater embodying my invention.

55 The same part is designated by the same

reference numeral wherever it occurs throughout the several views.

In accordance with my invention, I provide a heater for heating the bodies of automobiles in winter time, which utilizes the 60 waste gases of the exhaust from the motor of the automobile.

In my preferred form, I employ a water jacket around the gas passage, which forms the heater proper. The advantages in employing the water heater are obvious. In the first place it avoids the objection of all odor of poisonous gases from leaky joints or porous castings. Secondly, due to the fact that the usual gas heater becomes as heated 70 as the exhaust and passes through the floor boards of the car, I avoid the hazard of fire due to the heater pipe scorching the wood of the floor boards. Thirdly, I avoid the possibility of the heater becoming so hot 75 as to burn the shoes of the occupants when the heater is in the form of a foot rest or to burn any other apparel of the occupants in the car, or of the car's interior furnishings, when the heater is used in any 80 other form. Fourthly, I employ no open space in the floor boards of the car to allow the heater pipe to pass therethrough, which would result in dust or refuse from the street being swept into the car or rattle or other 85 noisy jar to be present. Fifthly, due to the fact that the pipes forming the heater are not restricted in diameter the exhaust gases are not retarded in their flow and the pulsation of the motor is not felt by the occupants in the car.

While it is obvious that the heater embodying my invention is not to be limited to such details as size, shape, material or form, I will now describe as one embodiment 95 of my invention, a form of heater, preferably water jacketed, and of metal which is made into a foot rest for the occupants of the car.

Referring to the drawing, 1 designates 100 the foot rest of the heater which in the form shown, but to which I am not to be limited, or restricted, is a cylindrical tube provided with two supporting cylindrical stanchions 2. Located within the cylinder 1 is a pipe 105 3 provided with two extensions 4 and 5 to communicate therewith and extending through the cylindrical supports 2, as shown. The pipe 3 is supported within the cylinder 1 in any suitable or desirable manner so as 110

to support the same within the cylinder, free from contact with any portion thereof to thereby prevent rattle due to impact between these two members caused by the vibration or jaw of the car. I show a simple and efficient means wherein the extensions 4 and 5 of the pipe 3 are torch-welded to the base portion of the supports 2, completely around the circumference thereof as shown. 10 It will be seen that by this arrangement I provide a water jacket completely around the pipe 3 and around the portions of the projections 4 and 5 thereof which lie within the supports 2. It is apparent that 15 the size of the water jacket may be varied at will by increasing the size of the cylinder 1, or decreasing the size of the pipe 3, or both. Extension 5 of the pipe 3 is connected in any suitable manner to the exhaust line 20 of the motor, preferably between the motor and the muffler. The efficient connection for this purpose, I find to be a flexible pipe, not shown. The extension 4 of the pipe 3 is connected to exhaust in any suitable, well 25 known manner. Supports 2 of the cylinder 1 are provided with a circumferential flange 7, located a short distance above the bottom end of the support as shown. These flanges are adapted to be secured to the flooring 8 30 of the car body to hold the heater in position. It will be seen that the water jacket about the extensions 4 and 5 of the pipe 3, which I will hereinafter refer to as the outlet and inlet pipe, extends below the body floor so 35 that the fire hazard due to the hot gases setting fire to the flooring, is completely eliminated, when water is supplied to the heater. Any suitable means may be employed for allowing the cylinder 1 to be 40 filled with water or other fluid. In practice, I prefer to place the filling mouth or neck communicating with the interior of the cylinder 1, offset relative thereto and in the rear thereof to thereby move the same out of 45 possible contact with the feet of the occupants of the car, when the heater is used as a foot rest. I have shown such an arrangement wherein the cylinder 1 is provided with a neck 9, which is adapted to receive a plug 50 10 therein, which, in the form shown, is a screw plug.

One of the special features of my invention is to provide means for preventing the heater from exploding in case steam is generated therein. To this end, I show the plug 10 as being provided with a blow-off valve 11 of any desired or well known structure, the valve head of which is normally retained seated by a spring 12, as shown. If 55 desired, means may be employed for draining the water from the interior of the cylinder 1 to prevent injury thereto, due to freezing when the car is laid up in cold weather. I provide a pipe 13 located at the bottom 60 portion of the cylinder 1, which is provided

with projections extending into the supports 2 down to the approximate bottoms thereof. The pipe 13 also passes through the cylinder 1 and the flooring 8 and is provided with a stop-cock 14, whereby, when it is desired, 70 to drain the water from the cylinder 1, the stop-cock 14 is opened and the pipe 13 consequently acts as a siphon, thus allowing the water to drain from the cylinder 1 and be discharged beneath the car into the road. 75 By having the pipes 13 project downwardly into the bottom of the supports 2, it will thus be seen that practically the entire amount of water within the cylinder 1 may thus be drained off. 80

To afford ready control of the heater and thus enable the occupants of the car to regulate the heat supplied thereto, I provide a throttle 20 located within the intake pipe 5, which is of equal diameter therewith, and which may be controlled from the interior of the car to open or close the intake pipe 5 to any desired degree. I accomplish this by means of levers 21 and 22, which are pivotally secured to each other, the lever 22 85 passing through the flange 7 of the support 2 and being provided with a spring 23 acting to normally pull the lever upwardly to close the intake pipe 5, by means of the throttle 20, by rocking the same about its 90 pivotal axis. The lever 22 is also provided with notches 25 adapted to engage the flange 7 where the lever 22 passes therethrough to hold the throttle 20 in any desired adjusted position against the action of the spring 23, as 95 will be readily understood. If desired, and as shown in Fig. 2, a spring guide 26 secured to the under surface of the support 2 may tend to normally press the lever 22 outwardly into 100 engaging relation with the flange 7, to thereby prevent the vibrations or jar of the car from varying the adjustment of the heater. 105

This valve or throttle can obviously be controlled by the foot. From the foregoing it is seen that I have provided a simple and efficient heater, the installation of which is simple and requires only two 2" holes in the floor board and a tap into the exhaust pipe for the flexible connection thereto. There is no rattle as there are no joints to 110 work loose and there are no rivets to shear or become noisy. It is obvious that the heat is distributed evenly and the water within the cylinder 1 remains heated for some time after the motor has been stopped, which is 115 an obvious advantage. Due to the construction of the tubing, the gases are constantly expanded and there consequently is no pulsation of the motor felt in the car. The smell of hot metal is eliminated due to the 120 water jacket feature, and though the heat secured is amply sufficient, it never becomes greater at any time than 212° F. Further, the objection of creating back pressure upon 125 the motor is eliminated due to the fact that 130

- the outlet for the gas with the heater attached is larger than it is before the heater is installed. Because of the fact that hot water entirely surrounds all of the parts of 5 the heater inside the car, the character of the finish of the cylinder 1 is not restricted, and it is obvious that nickel or copper plate, bronze and aluminum plate may be used, or in fact any desired finish may be used to 10 conform with the interior finish of the car without the danger of same becoming cracked due to the heat of the heater and thus afford an unsightly heater for an otherwise artistically finished car body.
- 15 While I have shown and described a specific embodiment of my invention, I wish it to be understood that many modifications will occur to those skilled in the art without departing from the spirit and scope thereof.
- 20 For example, while I deem the use of a water jacket to be preferable, the water may be eliminated therefrom and the cylinder 1 may be perforated, as shown in Fig. 5, and thus secure the benefits of a heater by hot 25 air. It is obvious that many other variations and modifications and details will occur to those skilled in the art.

While for the purposes of illustration I have described my invention as applied to an 30 automobile heater I wish it to be understood that the same can be used in connection with an explosion engine either stationary engine, aeroplane engine or any other type where it is desired to heat bodies by the exhaust gases 35 of the engine.

Having now set forth the nature of my invention, what I claim to be new and useful and desire to secure by Letters Patent is:

1. In a heater for explosive engine driven 40 vehicles, a pipe adapted to be in communication with the exhaust pipe of the engine, and extending through the car body, and a casing completely surrounding said pipe and the portions thereof extending through said 45 car body, to form a space between said pipe and casing, and an orifice in said casing for admitting water into the same, and a cap carrying a blowoff valve for said orifice.
2. In a heater for explosive engine driven 50 vehicles, a pipe adapted to be placed in communication with the exhaust pipe of the engine, and extending through the car body, and a casing completely surrounding said pipe and the portions thereof extending 55 through said car body, to form a space between said pipe and casing, and means for

admitting water into said casing and means comprising a siphon connection for draining the water from said casing.

3. In a heater for explosive engine driven 60 vehicles, a pipe adapted to be placed in communication with the exhaust pipe of the engine, and extending through the car body, and a casing completely surrounding said pipe and the portions thereof extending 65 through said car body, to form a space between said pipe and casing, and a foot actuated valve for controlling the amount of gas passing through said pipe.

4. In a heater, the combination with a casing provided with supporting extensions therefor, of a pipe located within said casing and provided with extensions located within the supporting extensions of said casing, said pipe and casing being welded together 70 at the bottom portion of said supporting extensions to make said casing water tight and to support said pipe in said casing out of contact therewith to form a space between said pipe and said casing at 75 all points.

5. In a heater, the combination with a casing provided with supporting extensions therefor, of a pipe located within said casing and provided with extensions located within 85 the supporting extensions of said casing, said pipe and casing being welded together at the bottom portion of said supporting extensions to make said casing water tight and to support said pipe in said casing out of 90 contact therewith to form a space between said pipe and said casing at all points and means located above the jointure of said pipe and casing for securing said casing to the automobile body. 95

6. In a heater, the combination, with a casing, provided with supporting extensions therefor, of a pipe located within said casing and provided with extensions located within the supporting extensions of said 100 casing and secured to the bottom portion of said supporting extensions to make said casing water tight, and means for admitting water into said casing, and a siphon controlled by a stop cock and having 105 projections extending into the supporting extension for draining the water from said casing.

In testimony whereof I have hereunto set my hand on this 14th day of January, A. D. 1918.

MILBOURNE KEITH DUNHAM.
